UNITED STATES PATENT OFFICE

91,960

DESIGN FOR AN AUTOMOBILE FLOOR MAT OR ANALOGOUS ARTICLE

Frank M. Netzel and Elmer F. Frost, Chicago, Ill.,
assignors to Frost Rubber Works, Chicago, Ill.,
a partnership consisting of F. S. Frost and
F. M. Netzel

Application February 5, 1934, Serial No. 50,627

Term of patent 14 years

To all whom it may concern:

Be it known that we, FRANK M. NETZEL and
ELMER F. FROST, citizens of the United States, re-
siding at Chicago, in the county of Cook and State
of Illinois, have invented a new, original, and or-
namental Design for an Automobile Floor Mat or
Analogous Article, of which the following is a
specification, reference being had to the accom-
panying drawing, forming a part thereof.

In the drawing:

Fig. 1 is a plan view on a somewhat reduced
scale of our new automobile floor mat;

Fig. 2 is a section taken on the line 2—2 of
Fig. 1;

Fig. 3 is a section taken on the line 3—3 of
Fig. 1; and

Fig. 4 is a full size fragmentary plan view.

What we claim is:

The ornamental design for an automobile floor
mat or analogous article, as shown.
